SAFETY CAGE FOR OIL DERRICKS

Nay Miles, Anahuac, Tex., assignor of one-third
to Guy C. Jackson, Jr., and one-third to H. L. D.
Scott, both of Anahuac, Tex.

Application August 12, 1939, Serial No. 289,869

2 Claims. (Cl. 304—14)

The present invention relates to oil derricks and similar structural devices and has for its primary object to provide a cage which is attachable in a suitable position to the side of the derrick and embodying a platform upon which a workman may stand while disconnecting the pipe or rod, or while performing other work on the derrick.

An important object of the invention is to provide a cage of this character of simple and practical construction, which is strong and durable, which may be easily and quickly attached to a desired position on the derrick and which is otherwise well-adapted for the purposes for which the same is intended.

Further objects and advantages reside in the details of construction as more fully hereinafter described and claimed, reference being had to the accompanying drawing forming part hereof, wherein like numerals refer to like parts throughout, and in which—

Figure 1 is a top plan view, and

Figure 2 is a sectional view taken substantially on a line 2—2 of Figure 1.

Referring now to the drawing in detail, the numeral 5 designates a pair of angle iron corner posts each having a flange 6 positioned in parallel opposed relation, as shown in Figure 1 of the drawing, and to which is secured the end portion of a U-shaped angle iron platform support 7 by means of rivets or the like 8. The support 7 includes a horizontal flange 9 and a vertical flange 10 and upon the horizontal flange is positioned a platform 11 which is coextensive to the internal area of the vertical flange 10. The platform 11 is preferably constructed of sheet metal and is provided with drain openings 12.

A plurality of U-shaped rails 13 also have their end portions secured to the flanges 6 of the posts 5, by means of rivets 14, or the like, the rails being positioned horizontally and in vertically spaced relation as shown in Figure 2 of the drawing. A pair of vertical brace members 15 are connected at the opposite sides of the rails 13 as well as to the vertical flange 10 of the support 7 and a pair of diagonally extending brace rods 16 also extend from the upper rails 13, adjacent its inner end, and extend downwardly and outwardly and are connected to the support 7 at the bottom of the vertical braces 15.

The posts 5 extend upwardly above the uppermost rail 13 and below the support 7 and are provided at their upper and lower ends with J bolts 17 for clamping to the beams of the oil derrick or other structure (not shown).

From the foregoing it will be apparent that the workmen may stand upon the platform 11 and the rails 13 will serve as guards to prevent the workmen from falling from the platform.

It is believed the details of construction, utility and manner of use of the device will be readily understood from the foregoing without further detailed explanation.

Having described the invention what I claim is:

1. A safety cage for oil derricks and the like comprising a pair of upstanding angle iron posts, means for securing the posts to the derrick, said posts including flanges positioned in opposed relation and also including flanges extending toward each other to provide inner corners for the cage, a U-shaped angle iron platform support having its ends secured to said opposed flanges of the posts and extending horizontally therefrom said U-shaped support including a vertical flange and an inwardly extending horizontal flange, a platform supported on the horizontal flange of said support said second-named flanges of the posts and said vertical flange of the support cooperating to keep the platform on the support, a plurality of guard rails secured to said posts and arranged in vertically spaced relation above the platform and brace members connecting said guard rails to the platform support. 10 15 20 25

2. A safety cage for oil derricks and the like comprising a pair of upstanding angle iron posts, means for securing the posts to the derrick, said posts including flanges positioned in opposed relation and also including flanges extending toward each other to provide inner corners for the cage, a U-shaped angle iron platform support having its ends secured to said opposed flanges of the posts and extending horizontally therefrom said U-shaped support including a vertical flange and an inwardly extending horizontal flange, a platform supported on the horizontal flange of said support said second-named flanges of the posts and said vertical flange of the support cooperating to keep the platform on the support, a plurality of U-shaped guard rails having their end portions secured to said opposed flanges of the posts and extending horizontally in vertically spaced relation above the platform, vertical brace members connecting the guard rails and the platform support adjacent their outer portions and inclined brace members connecting the uppermost guard rails with said platform support. 30 35 40 45 50 55
